PURSE HOLDER

Alexander M. Gordon, 500 Coconut Isle,
Broward County, Fla. 33301
Filed July 12, 1965, Ser. No. 471,093
1 Claim. (Cl. 248—206)

My invention relates to a new and novel means of anchoring a woman's handbag or purse or other objects conveniently nearby within reach, leaving both hands free for other purposes.

It is known that when a woman with her handbag or purse seats herself at a bar, soda fountain, lunch counter or even a booth or table at a restaurant or safe, her handbag or purse becomes an immediate problem. If she places it on top of the bar, counter or table it becomes an awkward impediment; in her own way and also in the way of others because of the limited space available for eating and/or drinking. If she places the handbag or purse in her lap it forces her to sit in a strained and uncomfortable position to prevent the handbag or purse from sliding off to the floor. If she places it on the floor next to her, the handbag or purse is in constant danger of being inadvertently kicked or stepped upon either by herself or other persons in the immediate area. In this position it is also of course in danger of being stolen by a dishonest person.

Attesting to the fact that the conditions described above have been a constant and vexing problem, is the existence of a number of inventions attempting to directly solve or alleviate the problem of what can a woman do with her handbag or purse when she sits down at a bar, soda fountain, lunch counter, etc. to eat and/or drink.

One invention provided a metal rod bent into a U shape with a closed eye at one end of the rod to prevent surface marring and an open hook at the other end to receive the handle of the handbag or purse. The closed eye end of the U shape bar was laid on the surface of the bar, counter or table in such a manner that the open hook end was directly underneath, with the projection of the counter top or table top in between the legs of the U shape metal bar. The handle of the handbag or purse was placed in the open hook. Thus the handbag or purse was suspended underneath the projecting bar top or counter top.

Another invention provided a clamp with a short length of chain attached to the clamp and a hook provided on the other end of the chain to receive the handbag or purse the idea being to affix the clamp to the edge of the counter top or bar top and thus keep the handbag or purse out of the way.

These devices worked after a fashion but became totally useless with the advent of the current type of sloping quilted bar top or counter top.

My invention has for one of its objects to provide a firm anchorage to any smooth surface without marring or damaging that surface in any manner, and to this anchorage attaching a suitable length of decorative chain or cord with a suitable open hook on the end of the chain or cord to receive the handle of a woman's handbag or purse thus providing a means of anchoring a woman's handbag or purse from any smooth surface without marring or damaging said smooth surface in any manner.

Another object of my invention is to provide an anchorage of the character herein described that can be placed into use and removed again instantly without the use of tools, previous skill or dexterity.

Another object of my invention is to provide a device of the character described herein that will provide a means of suspending a woman's handbag or purse conveniently at her side so contents are accessible at anytime

2

without removing handbag or purse from the device while she is seated at a bar, counter, table or booth.

Still another object of my invention is to provide a handbag or purse anchorage that is completely self contained, that is decorative and novel, that retracts into a small compact item that is easily dropped into and carried in a woman's handbag or purse.

Still another object of my invention is to provide an anchorage of the character herein described for other purposes than a woman's handbag or purse such as brief cases, attache cases, one or more packages, walking stick, umbrella, etc.

Still another object of my invention is to provide a device of the character described herein at a very comparative low manufacturing cost with a basic design that can be mass produced in high volume with relative low tooling costs.

Still another object of my invention is to provide various combinations and arrangements of attaching and housing the component parts so that when the device is in use it presents a novel and highly interesting and mysterious appearance.

Other additional objects, benefits and advantages of this invention will become evident as the description of the invention proceeds.

FIG. 1 is a pictorial view of my invention showing its principal components.

FIG. 2 is a pictorial view of my invention in actual use showing the anchorage secured to the top of a counter and with a woman's handbag hanging from the hook.

FIG. 3 is an elevation showing a modification of my invention.

FIG. 4 is an elevation showing another modification of my invention.

FIG. 5 is a further modification of my invention.

In FIG. 1 and FIG. 2, 6 is the housing or container for chain 7 and hook 8. The housing or container 6 can be made of any sturdy material such as leather or plastic. 9 is a conventional suction cup, the suction face of which protrudes through the pocket of housing 6 by means of a hole in the pocket. The back of suction cup 9 is permanently fastened to the back of housing 6 by means of a rivet or other suitable means. One end of flexible chain 7 is also permanently affixed at the same point where the back of suction cup 9 and back of housing 6 are joined together. At the other end of chain 7 is open hook 8 which has a closed eye so it can be permanently affixed to end of chain 7. 10 is a snap fastener showing male and female respectively on the pocket and flap of the housing or container 6. When the device is out of use the chain 7 and hook 8 are tucked within the pocket of housing or container 6 and snap fastener 10 makes it secure when flap is folded over and snapped in place.

55 In FIGURE 2, showing the invention in actual use, 11 is a counter or table top, not a part of the invention and 12 is a lady's handbag also not a part of the invention.

In FIGURE 3 which shows a modification of my invention, 13 is the housing or container in the form of a hollow figure such as a dog. The suction cup 14 is permanently affixed to the underbelly of the housing 13 which is in the form of a hollow dog. In the breast of the dog is a suitable aperture 15 whereby the chain 16 and hook 17 can be pushed inside the hollow dog for compactness.

65 FIGURE 4 illustrates another modification of my invention wherein the end of chain 18 and hook 19 are permanently affixed to flap of housing or container 20. At the other end of chain 18 is affixed the suction cup 21.

70 FIG. 5 is another modification of my invention showing three of the basic components such as suction cup 22, chain 23 and hook 24 with no housing.

In operation the suction cup is pressed flat on the counter top or top of bar 11. Wetting the face of the suction cup before applying to the surface enhances the efficacy of the suction cup by providing a better seal for the suction. Hanging the woman's handbag or purse on the hook completes the operation. Location of the suction cup on the counter or bar in relation to distance from the user determines the height of the handbag so it is always convenient for access.

While this invention has been explained and described with reference to certain specifically contemplated embodiments, it will nevertheless be understood that these disclosures are illustrative and not restrictive. The few examples of the usefulness of this invention in many fields disclosed herein and the many combinations and forms the principal components can be made up in and assembled are too numerous to mention here.

Having thus described my invention I claim:

A purse holder comprising

- (a) a container for holding a purse support chain,
- (b) a suction cup located on one side of said container,
- (c) a support chain attached to the inside of said container,

5

10

15

20

- (d) said container having fastening means thereon for opening and closing said container,
- (e) said chain being retractable within said container and extendable to its full length outside said container,
- (f) an open hook member on the end of said chain, and
- (g) said hook member being engageable with the links of said chain so as to provide a chain support of varying lengths.
